UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

CHEEK PLATE.

1,407,978.

Specification of Letters Patent. Patented Feb. 28, 1922.

Application filed May 31, 1918. Serial No. 237,484.

To all whom it may concern:

Be it known that I, DONALD S. BARROWS, a citizen of the United States, residing at Rochester, in the county of Monroe and 5 State of New York, have invented certain new and useful Improvements in Cheek Plates; and I do hereby declare the following to be a full, clear, and exact description of the invention, such as will enable others 10 skilled in the art to which it appertains to make and use the same.

The invention relates to draft rigging for railway cars, and more particularly to cheek-plates or stop castings which are primarily 15 desired for use with tandem spring draft rigging.

The principal object of my invention, broadly stated, is to provide a tandem spring cheek-plate furnished with the usual number 20 of stops for the followers of the draft rigging and provided with a series of rivet receiving openings or pockets, the pockets being so related to the structural features of the plate as to form therewith a plurality of angular 25 inwardly projecting members which reinforce the said plate and prevent the buckling of the same under loads.

Another object of the invention is to construct a cheek-plate in which some of the 30 rivet receiving pockets are so disposed and related that they form means for strengthening the cheek-plate against deformation.

There are other objects of the invention relating to the various features thereof, as 35 will hereinafter clearly appear in the more detailed description of the invention when the same is taken in connection with the accompanying drawing which has been chosen to illustrate the same, and in which,

40 Figure 1 is a side elevation of a cheek-plate embodying my invention,

Figure 2 is a top plan view of the plate illustrated in Figure 1,

Figure 3 is a longitudinal transverse section of Figure 1, and

45 Figures 4, 5 and 6, are, respectively, transverse vertical sectional views taken on lines 4—4, 5—5 and 6—6 of Figure 1, looking in the direction indicated by the various 50 arrows.

Throughout the specification and drawing like parts are designated alike.

The cheek plate 1 is provided with a plurality of main stop shoulders 2, 3 and 4, and 55 with a plurality of intermediate or limiting

stop shoulders 5 and 6. The main stop shoulders are preferably formed as inwardly projecting flanges 7, the said flanges are adapted to extend inwardly from the portions 8 of the web of the said cheek-plate. 60 The said portions 8 are adapted to form the rear face of the said plate, that is the portions of the said plate which is adapted to contact the adjacent face of the car sill to which the plate is attached. The said flanges 65 7 are also adapted to form T-sections with the portions 9 of the said cheek-plate web which are located between the main stop shoulders and which are spaced from the portions 8 of the web. To reinforce and 70 provide additional wearing area the inner faces of the main stops 2 and 4 are provided, respectively, with forwardly and rearwardly extending lips or flanges 10, and to strengthen the flanges 7 which form the 75 front and rear faces of the middle stop 3 they are provided with a plurality of bracing ribs 11 which connect the flanges 7 intermediate the upper flange 12 and the lower rib 13 thereof. To increase the wearing area 80 of the said middle stop the bracing ribs 11, as well as the flange 12 and the rib 13, are provided with lips 14, the outer faces of which are in line with the outer edges of the said intermediate flanges 7 which form 85 the side walls of the middle stop 4.

The intermediate stop shoulders 5 and 6 are each preferably formed as convolutions or bends in the portions 9 of the web of the casting, and it will be clear from an inspection of the drawings, particularly Figures 2 and 3 thereof, that in the casting process the front, middle and rear stops will be cored from the front of the plate, and that the intermediate stops 5 and 6 will be cored from 90 the rear. This method of coring simplifies the manufacture of the cheek-plates and greatly reduces in the manufacturing process the production of faulty or damaged castings. 95

Intermediate the flanges 7 of the main stop shoulders the cheek plate is provided with a plurality of rivet receiving openings 15 which are preferably arranged in substantial alinement. The metal immediately 100 surrounding each rivet hole is countersunk, as shown at 16, so as to provide rivet head receiving pockets 18. The countersunk rivet pockets not only provide means whereby 105 the rivet heads are placed below the adj- 110

cent web of the cheek-plate, but also provide a firm riveting area for the intermediate portion of the cheek-casting, since the outer faces of the bottom walls 16 of the said pockets are arranged in line with the outer or sill-adjacent portions 8 of the web of the cheek casting. The adjacent portions of the side walls 19 of each two adjoining pockets 18 are adapted to form wedge shaped braces 20 which extend inwardly from the back wall of the casting to the inner face of the portion of the web adjacent each wedge shaped projection. The portions of the flanges 7 of the middle stop 3 which would intersect the adjacent rivet pockets 18 are also preferably inwardly tapered as shown at 19^a so as to form with the connecting rib 11 of the said middle stop a blunt wedge 20^a. To maintain a constant or substantially constant thickness of web the wedge shaped projections 20 are hollowed out or undercut as shown at 21.

Having now fully described my invention, although it is to be understood that by the foregoing I do not intend to limit the same, since the words used are to be understood in their descriptive and not in their limiting sense, what I claim and desire to secure by Letters Patent is:

30. 1. A cheek-plate for tandem spring draft rigging, said plate being provided with a plurality of main stop shoulders and a plurality of intermediate or limiting stop shoulders, a series of spaced rivet head receiving 35 openings countersunk in the web of the said plate, each opening being adapted to receive a single rivet only a portion of the wall of each opening merging into one of the stop shoulders of the said plate.
40. 2. A cheek-plate for tandem spring draft rigging, said plate being provided with a plurality of stop shoulders and further provided with a longitudinally arranged series of separated rivet head receiving pockets,

the adjacent portions of the side walls of 45 each two adjoining pockets forming a wedge shaped projection, the said projections being adapted to reinforce and strengthen the said plate.

3. A cheek-plate for draft rigging provided with a cast metal web and further provided with a longitudinally arranged series of separated rivet head receiving pockets countersunk in the said web, portions of the side walls of each two adjacent pockets forming 55 wedge shaped members.

4. A cheek-plate for tandem spring draft rigging provided with a plurality of main stops and a plurality of intermediate stops, said intermediate stops being interrupted by a pair of the rivet head receiving pockets, wedge shaped members forming portions of the side walls of the said last named pockets serving to connect the interrupted portions of the said intermediate stops.

5. A cheek-plate for tandem spring draft rigging provided with a cast metal web, a series of main stops and a plurality of supplemental stops formed in said web, portions of said web being countersunk and adapted to form the rear wall of said plate, and braces extending from the rear wall of said plate towards the inner or front face thereof between said main stops and the respective adjacent supplemental stops, said braces being wedge shaped in longitudinal section.

6. A cheek-plate for tandem spring draft rigging provided with a front stop, a rear stop, and a middle stop, the said middle stop 80 extending the full height of said plate, two series of rivet head receiving pockets countersunk in the web of the said plate, the said middle stop serving to separate the two series, the adjacent side walls of each two adjoining pockets being wedge-shaped.

In testimony whereof I affix my signature.
DONALD S. BARROWS.
